CARBURETOR

James T. W. Moseley, Webster Groves, Mo.

Application January 30, 1936, Serial No. 61,474

10 Claims. (Cl. 123—122)

This invention relates to carburetors for internal combustion engines and consists in novel means for applying heat to restricted portions of the carburetor, particularly adjacent the idle ports and throttle valve.

It has been found that when internal combustion engines are operated in cold weather, frost and ice frequently form on and around the carburetor idle ports and throttle valve, resulting in operating difficulties. This is due to the vaporization of the fuel and the expansion of air as it passes the throttle restriction, and may occur before the engine becomes fully heated after starting. Thermal insulators inserted between the carburetor and adjacent parts of the engine to minimize percolation and other difficulties caused by excessive heat, obviously aggravate the above-described condition with respect to formation of snow and ice during idling before the engine has become hot.

One object of the present invention is to provide means for counteracting the above-mentioned cooling effect.

Another object is to provide a device for the local application of heat to the carburetor at a point adjacent the idle port.

A further object of the invention is to provide a device of the above described character having means for cutting off the supply of heat when the temperature is high so as to avoid the aggravation of the difficulties which are caused by excess heating of the carburetor.

A further object of my invention is to provide an electrically operated heating device of the above described character.

A further object of this invention is to provide a simple and inexpensive construction by which heat may be conducted from the exhaust manifold to that portion of the carburetor in the vicinity of the idle discharge ports.

Other objects and advantages will appear upon reference to the following specification and drawings. Referring to the drawings:

Figure 1 is a diagrammatic sectional view of a carburetor attached to a portion of an intake manifold, and embodying one form of my invention.

Figure 2 is a sectional view taken on line 2—2 of Figure 1.

Figure 3 is a sectional view taken on line 3—3 of Figure 1.

Figure 4 is a diagrammatic sectional view of a carburetor embodying a second form of my invention.

Figure 5 is a partial view of the form in Figure

4 but showing the other side of the carburetor.

Referring to Figure 1 the reference numeral 1 indicates the main body of the carburetor, a flange 2 being provided at the lower end thereof for attachment to the intake manifold. The carburetor comprises an air inlet 3, mixture chamber 4, venturi 5, and mixture outlet 6 communicating with the intake riser 25 whereby the riser forms part of the carbureted mixture passage. The air inlet is controlled by a choker valve 7 mounted for rotation with pivotal shaft 8 and may be operated manually or automatically in any suitable manner. The outlet is controlled by throttle valve 9 rigidly mounted on pivotal shaft 10.

Fuel is supplied to the carburetor through intake 11 and is maintained at a constant level in the chamber 12, substantially as shown, by float 13 and needle valve 14. For normal and high speed operation, fuel is supplied to the mixture chamber through calibrated orifice 15 and passage 16 and is discharged by nozzle 17. For low speed operation, fuel is supplied through the calibrated orifice 18 and idle passages 19, 20, and 21 and is discharged adjacent the throttle valve through ports 22 and 23.

The specific construction of fuel passages, air bleeds, and discharge ports for supplying low speed or idling mixtures forms no part of this invention, and any suitable arrangement may be used for this purpose.

A flange 24 is provided at the upper end of riser portion 25 of the intake manifold for attachment of the carburetor as by means of studs 26 and nuts 27. A heat insulating spacer 28 is inserted between the flanges on the carburetor and intake manifold to prevent the rapid transfer of heat to the carburetor in such quantities as would cause percolation and other difficulties.

A stove or "hot spot" 29 encloses a portion of the intake manifold 25 for the purpose of heating it with exhaust gas which may enter at 30 and pass out of an opening 31 (shown dotted) behind the intake manifold. It will be understood that the heat supply to this stove may be cut off by automatic means when the temperature is above normal. The means for controlling the heat supply may be of the type shown in Bicknell application Serial No. 584,660, filed January 4, 1932.

In order to apply small amounts of heat to the idle port in sufficient quantities for the purpose described without supplying so much heat as to cause the whole carburetor to be over-heated, I provide vertical passages 32 and 33 extending upward from the lower end of the carburetor and

connected at their upper ends by cross passage 34 to form an inverted U passage. The lower ends of passages 32 and 33 are provided with pilot tubes 35 positioned with their flared openings 5 facing in opposite directions so as to induce the flow of exhaust gas through these passages in the manner indicated by the arrows.

In operation, upon starting a cold engine under low temperature conditions, exhaust gas enters 10 the "hot spot" and a portion passes through the passages 32, 33 and 34 thereby immediately applying heat to that portion of the carburetor in the vicinity of the idle ports and throttle valve, thus preventing the formation of frost and ice at 15 these points.

When the temperature is excessive the application of exhaust heat to the hot spot 29 may be cut off as, for instance, by the automatic means described in the above mentioned co-pending 20 application so that the operation of the idle port heating device is discontinued when it is not required.

A modification of my invention is shown in Figures 4 and 5 of the drawings in which a hermetically sealed resistance coil 36 is applied adjacent the idle port 22 for the purpose of heating the adjacent parts of the carburetor. Current for heating this coil is supplied by the storage battery 37, one terminal of which is connected to 30 the coil by means of conduit 38. The coil is also connected by conduit 39 to switch member 40 which slidably contacts rotor 41 attached to choker shaft 8. Shaft 8 is electrically connected with the other battery terminal through the body 35 of the carburetor and conduit 42. The battery, switch and coil may be electrically connected by other means, if desired. Lead 38 also breaks through a manual switch 45, which may be the usual ignition switch, so that the application of 40 heat will be cut off when the engine is not in operation.

A current insulating inlay sector 43 is provided in the rotor for the purpose of breaking the circuit when the choke valve is in an open or nearly 45 open position.

The end of choke shaft 8 opposite the switch members 40 and 41 extends into a chamber 46 housing a thermostatic coil 47 which is operatively connected to shaft 8 so as to yieldingly resist 50 opening of the choke valve when the temperature is relatively low and to move the valve to the open condition responsive to the heated condition of the engine.

In operation, upon starting a cold engine in 55 cold weather, the choke valve will be moved to a closed position, and the ignition switch will be closed, thereby connecting the battery and heating coil whereupon the coil will radiate heat in the vicinity of the idle discharge ports and the edge of the throttle valve adjacent the ports, thus preventing the formation of frost and ice.

As the engine warms up the choke valve is gradually moved toward its open position by the thermostat and when the choke is fully opened 65 switch member 40 engages insulating sector 43 breaking the circuit to the resistance coil. At this time the engine heat at the lower end of the carburetor will be sufficient to prevent further frosting adjacent the throttle and fuel nozzles.

60 In addition to preventing the formation of ice around the idle port, the electrically heated device shown in Figures 4 and 5 serves as a fumer and substantially assists vaporization and starting under low temperature conditions.

75 The devices illustrated are susceptible of var-

ious modifications without departing from the spirit of the invention and the exclusive use is contemplated of all such modifications as come within the scope of the appended claims.

I claim:

1. In an internal combustion engine, structure forming a fuel mixture chamber, a fuel passage having an opening into said chamber, means for heating a restricted portion only of said structure adjacent said opening to counteract the cooling effect due to vaporization of fuel in said opening, and means for avoiding the effect of said heating means when the engine becomes heated. 5

10 2. In an internal combustion engine, structure forming a fuel mixture chamber, a liquid fuel chamber having an opening into said mixture chamber, means for confining a body of fluid matter exposed to the engine heat, and means for conducting said fluid matter to a portion of 20 said structure adjacent said opening for heating said portion, the heated fluid in said conducting means affecting a restricted portion only adjacent said opening.

25 3. In an internal combustion engine, carburetor structure including a mixture chamber, a liquid fuel chamber, and an idling fuel passage connecting said chambers, said passage having an opening in the wall of said mixture chamber, heating means, and a conduit leading from said 30 means to a portion of said structure adjacent said opening for heating the same and then leading back to said means.

35 4. In a carburetor, structure forming a fuel mixture chamber, a liquid fuel chamber having an opening into said mixture chamber, means for heating said structure adjacent said opening, and means responsive to the heated condition of the engine for avoiding the effect of said heating means. 40

45 5. In a carburetor, structure forming a mixture chamber, a choke valve therein, a fuel passage having an opening into said mixture chamber, an electrical unit for heating said structure immediately adjacent said opening, and a switch operated by said valve for controlling said unit; in which said switch comprises contact members, one of said members being rotatable with said valve and having an electrical conducting part and an insulating part, and the other member being formed of an electrical conductor, said switch being closed when said second-mentioned member is in engagement with the conducting part of said first-mentioned member, and open when said second mentioned member is 50 in engagement with the insulating part of said first-mentioned member. 55

60 6. In a carburetor, structure forming a mixture conduit, a throttle valve therein, an idling port in the wall of said conduit adjacent said valve, means for heating a portion of said conduit spaced from said valve for improving vaporization in 65 said conduit, and individual means for heating a restricted portion only of said structure immediately adjacent said port for counteracting the cooling effect due to vaporization of fuel in said port and adjacent said valve. 65

7. In a carburetor, structure forming a fuel mixture conduit, a liquid fuel chamber having an opening into said conduit, means for heating a portion of said conduit spaced from said opening for improving vaporization in said conduit, and an electrical heating unit immediately adjacent said opening for heating said structure. 70

8. In a plain tube carburetor, means forming 75

a mixing conduit, a venturi in said conduit, a main fuel nozzle discharging in said venturi, a throttle valve, an idle passage discharging into said mixing conduit at the edge of said throttle valve and a heating device for applying heat to said idle discharge passage without substantially heating the fuel supply from the main nozzle.

9. In a plain tube carburetor, means forming a mixing conduit, a main fuel discharge nozzle discharging into said mixing conduit, an idle passage for discharging idling fuel into said mixing conduit and means for raising the temperature of the idling fuel to a degree substantially

higher than the temperature prevailing in the mixing conduit generally.

10. In a device of the class described, a mixing conduit, a main fuel nozzle discharging into said mixing conduit, an idling fuel passage discharging into said mixing conduit, a device for heating said idling fuel passage and additional means posterior to the discharge outlet of said idling fuel passage for applying heat to said mixing conduit. 5 10
